UNITED STATES PATENT OFFICE.

HUGO MAUL, OF RAHWAY, NEW JERSEY.

DESIGN FOR A SKIRT-PROTECTOR.

SPECIFICATION forming part of Design No. 29,803, dated December 13, 1898.

Application filed July 9, 1898. Serial No. 885,530. Term of patent 7 years.

To all whom it may concern:

Be it known that I, HUGO MAUL, of Rah-
way, in the county of Union and State of New
Jersey, have invented and produced a new
and original Design for a Skirt-Protector, of
which the following is a full, clear, and exact
specification.

Reference is to be had to the accompanying
drawings, forming a part of this specification,
in which similar characters of reference indi-
cate corresponding parts in both the figures.

Figure 1 is a face view of a piece of a skirt-
protector, showing my design; and Fig. 2 is a
transverse section thereof on the lines 2 2 in

Fig. 1.

The skirt-protector consists of the head A,
having a plain upper edge, the brush B, pend-

ent from the lower edge of the head, and the
two longitudinal rows of spaced ornaments C,
extending transversely of the head and ap- 20
pearing raised on the sides of the said head,
the ornaments of one row being arranged al-
ternately with those of the other row, the up-
per ends of the ornaments of the lower row
being in line with the lower ends of the orna- 25
ments of the upper row.

I claim—

The design for a skirt-protector, as herein
shown and described.

HUGO MAUL.
